UNITED STATES PATENT OFFICE.

EARL C. POTTER, OF CHICAGO, ILLINOIS.

PACKING OR SHIPPING BOX.

1,159,338.

Specification of Letters Patent.

Patented Nov. 2, 1915.

Application filed September 28, 1912. Serial No. 722,879.

To all whom it may concern:

Be it known that I, EARL C. POTTER, a citizen of the United States, residing at Chicago, in the county of Cook and State 5 of Illinois, have invented certain new and useful Improvements in Packing or Shipping Boxes, of which the following is a specification.

My invention relates to packing or shipping boxes made of paper board, preferably doubled-faced corrugated paper board, and more particularly intended and designed for the packaging and shipment of potted flowers.

15 The object of my invention is to produce a simple and efficient box of this character of the collapsible or knock-down type which shall be comparatively simple and inexpensive of manufacture and capable of being 20 readily assembled and manipulated by the user.

In the drawings Figure 1 is a plan view 25 of a blank cut and scored to form the body of the box; Fig. 2 a similar view of one 30 of the inner linings or supports for the box, but on a larger scale; and Fig. 3 a vertical section of an assembled box illustrating a potted flower contained and supported therein, said view being on the same scale 35 as Fig. 2.

Referring to the particular embodiment 40 of my invention as illustrated in the drawings, the box body is formed from the blank shown in Fig. 1, which blank is of any desired dimensions and is preferably made of 45 double-faced corrugated paper board in order to provide the desired strength. This blank consists of a bottom 1, two long side walls 2—2 hinged thereto along score lines, 50 end walls 3—3 also hinged to the bottom 1, and in addition the four corner flaps 4 which are hinged to the end walls 3 but separated from the side walls 2 by means of the slits 5.

It will be understood that as a matter 55 of convenience of description I have referred to the section 1 of the blank as the bottom, although when the box is erected and standing in the position illustrated in Fig. 3 it constitutes one of the side walls 60 equally with the two similar and opposite walls 2, the fourth wall consisting of a lid or cover (not shown) which may be of any usual construction. In forming the box body the side walls 2—2 are folded upwardly to a position at right angles to the 65 bottom or wall 1 and the two end walls

3—3, which may also be considered as constituting top or bottom closures as the case may be, are likewise folded upwardly to a position at right angles to the bottom or 60 wall 1, and the four corner flaps 4 are folded to a position inside of the box thus formed and against their adjacent side walls 2. These corner flaps may be retained in position in any suitable manner as by means of 65 the hooks or staples 6 which are pressed into the corrugations in said side walls and flaps.

Within the box body are secured two lining and supporting boards which are similarly made from a blank such as illustrated in Fig. 2. This blank consists of a rectangular sheet of double-faced corrugated paper board with a width equaling that of one of the side walls of the box body, 75 and of a length to extend from one of the free edges of the corner folds at the top of the box to the lower end of such box, including the folding thereof inwardly toward the center of the box in a position 80 above the pot of the plant. As shown, this blank is transversely scored so as to form the four sections 7, 8, 9 and 10. The top sections 7 and 10 when in place within the box press against one of the side walls 2 85 thereof, and are secured thereto in suitable manner as by means of the staples 11, and 11^a. The next section, 8, is bent so as to diverge inwardly. The next section, 9, is bent or folded to press upon the top of the 90 pot 12. The remaining section 10 bears against the inner surface of one of the corner flaps 4. By preference I interpose between the bottom of the body and the end or bottom closure 3 a square strip of corrugated board 13.

It will be understood that in order to accommodate the different standard sizes or heights of pots employed, the blank shown in Fig. 2 is scored accordingly, but in each instance provision is made for the inward divergence or folding of two sections of such blank in the manner above explained. These inner boards serve not only to strengthen the box body at the two opposite 105 side walls, but also to provide a support and means for holding the pot at one end of the box, thereby preventing the movement of the potted flower and its pot within the box.

The blanks are shipped to the user or 110 consumer in the collapsed condition shown in Figs. 1 and 2, and such user is supplied

with the fasteners 6 and staples 11, together with a suitable tool for cleching the latter. The fasteners 6 are made and used in the manner shown in Ferres Patent No. 869,833, dated October 29th, 1907.

I claim:

1. A packing or shipping box for potted plants comprising a box body and strips arranged inside said body at two opposite sides thereof, said strips each having end portions lying against the inner face of the side walls of the box and each having a pair of intermediate sections folded to form an inwardly projecting abutment, and means for preventing endwise outward movement of the end portions of the strips.
2. A packing or shipping box for potted plants comprising a box body and strips secured to two opposite side walls and each being transversely scored to form sections 7, 8, 9 and 10, of which the sections 7 and 10 are secured to the box body and the sections 8 and 9 folded to project inwardly into the interior of the box.
3. A packing or shipping box comprising three side walls 1, 2, 2, hinged together, one of said walls 1 having end extensions to form end walls 3, and said end walls having on two opposite sides flaps 4 which are folded within and against the walls 2, and two opposite strips each having end portions

lying against the inner face of the adjacent wall 2 and having a pair of intermediate sections folded to form an inwardly projecting abutment, each end portion at one end of the strip abutting against an end of the adjacent flap 4 at that end of the box, and means for maintaining the end portions of the strips in contact with the side walls of the box.

4. A packing or shipping box comprising three side walls 1, 2, 2, hinged together, one of said walls 1 having end extensions to form end walls 3, and said end walls having on two opposite sides flaps 4 which are folded within and against the walls 2, and two opposite strips each having end portions lying against the inner face of the adjacent wall 2 and having a pair of intermediate sections folded to form an inwardly projecting abutment, each end portion at one end of the strip abutting against an end of the adjacent flap 4 at that end of the box, and each end portion at the other end of the strip abutting against the other end of the box, and means for maintaining the end portions of the strips in contact with the side walls of the box.

EARL C. POTTER.
